(57) **CLAIM**

The ornamental design for a see through tabletop game, as shown and described.

DESCRIPTION

FIG. 1 is a perspective view of a see through tabletop game showing our new design;

FIG. 2 is a right side elevation view thereof,

FIG. 3 is a left side elevation view thereof,

FIG. 4 is a front side elevation view thereof,

FIG. 5 is a back side elevation view thereof;

FIG. 6 is top plan view thereof; and,

FIG. 7 is a bottom plan view thereof.

The broken lines are for illustrative purpose only and form no part of the claimed design.
